A. A. WILSON.

SASH FASTENER.

APPLICATION FILED OCT. 4, 1919.

1,351,936.

Patented Sept. 7, 1920.

UNITED STATES PATENT OFFICE.

ANDREW A. WILSON, OF NORFOLK, VIRGINIA.

SASH-FASTENER.

1,351,936.

Specification of Letters Patent. Patented Sept. 7, 1920.

Application filed October 4, 1919. Serial No. 328,391.

To all whom it may concern:

Be it known that I, ANDREW A. WILSON, of Norfolk, in the county of Norfolk, State of Virginia, have invented certain new and useful Improvements in Sash-Fasteners; and I do hereby declare the following to be a full, clear, and exact description of the invention, such as will enable others skilled in the art to which it appertains to make and use the same.

My object is to provide a simple and inexpensive device so located as to practically prevent its being tampered with, and one which allows one sash to be held locked while the other is free to be moved.

In the drawing Figure 1 is a perspective section showing the application of my device to a window, while Figs. 2, 3 and 4 are details.

The window frame is indicated generally at 1 and its inner side at 2. 3 and 4 are, respectively, the lower and upper sashes, and 5 designates one of the beads mounted in the frame between the grooves in which the sashes move. The lock is mounted on this bead and is operated by a key 6 projected into an aperture 7 extending into the pulley stile 8 of the frame from its inner edge.

I have shown each of the sashes formed with notches 9 on their opposed faces near their side edges, that is, at the portions of the sashes which are in contact with the bead 5.

The lock as an entirety consists of a casting 10 having apertured plates 12 by which it may be attached, as by screws, to the inner face of the stile 8, the stile being recessed to receive the plates so that they will lie flush with the surfaces of the sash grooves. The lock is made with a housing projecting from each side of the plates 12. The projection 14 fits within a countersunk recess 15 formed in the stile and the bead 5 is interrupted to provide a space to receive projection 16 of the housing, this projection being formed in exact correspondence with the bead so as to form part of it. Near the upper and lower ends of its side walls projection 16 is formed with openings 17 adapted to register with the notches 9 of the sashes.

18 is the locking lever. It is of substantially S-shape in side elevation with a cam surface 18^a on one side and is fulcrumed at 55 about its central portion in the projection 16

of the housing so that its extremities may extend through openings 17 into the notches 9 of the two sashes. I make the upper angular extremity 19 of the lever 18 relatively longer than the lower one 20. This enables me to hold the lever in such position that the upper sash is locked while the lower one is free to be moved. A further turn of the lever will lock both sashes and a complete turn in the opposite direction will release both sashes.

The means for actuating the lever 18 is mounted in the projection 14 of the housing. It consists of a bell crank lever 23 whose fulcrum pin 24 terminates in a square head 25 adapted to register with the aperture 7 in the stile and be received by the key 6. In the vertical disposition of the lock when in place the upper arm 26 of the bell crank is longer than the lower arm 27, and both arms are beveled at one side as at 28, 29.

By the means described the operation of the key and consequent partial rotation of the bell crank 23 will cause the locking lever 18 to shift in a plane at right angles to that of the bell crank. When the longer arm 26 of the bell crank contacts with the cam 18^a on the upper arm of the locking lever, that is, the arm having the longer extremity 19, the locking lever is capable of being turned farther than when it is acted upon by the short arm 27 of the bell crank contacting with the portion of the cam surface on its lower arm, that is, the arm having the shorter extremity 20. Consequently I am enabled to adjust the key 6 and bell crank 23 so that the upper sash is held locked while the lower sash is free to be moved. A further point of adjustment in one direction locks both sashes and a complete turn in the reverse direction frees both sashes.

Aside from the cheapness of manufacture the main advantage of a structure embodying my invention is that it is virtually burglar proof, there being no way to tamper with the lock as can be done when the lock operates in contact with the end edges of the sashes.

I claim as my invention:

1. A sash fastener comprising a substantially S-shaped locking lever having beveled surfaces at each side of its fulcrum, and a bell crank lever movable in a plane at right angles to that of said locking lever and hav-

105

110

ing its arms beveled to co-act with the arms of said locking lever, and means for actuating said bell crank lever.

2. A sash fastener comprising a substantially **S**-shaped locking lever having one of its arms longer than the other and formed with beveled surfaces at each side of its fulcrum, and a bell crank lever having arms of unequal lengths and movable in a plane at 10 right angles to that of said locking lever, said bell crank having its arms beveled to co-act with the arms of said locking lever, and means for actuating said bell crank.

3. In a sash fastener, the combination 15 with a pair of sashes having notches on their inner contiguous surfaces, of a lock comprising a substantially **S**-shaped locking lever adapted to engage the notches of both sashes, a bell crank lever for turning said

locking lever on its fulcrum, and means for actuating said bell crank.

4. In a sash fastener, the combination with a pair of sashes having notches, of a lock comprising a substantially **S**-shaped locking lever adapted to engage the notches 25 of both sashes, the arm of said lever engaging one sash being longer than the arm engaging the other sash, and means for turning said lever on its fulcrum.

5. As an article of manufacture, a sash 30 fastener comprising a substantially **S**-shaped locking lever, a bell crank for shifting said locking lever, and a key for rotating said bell crank.

In testimony whereof I have signed this 35 specification.

A. A. WILSON.
